UNITED STATES PATENT OFFICE.

HENRY M. CHANCE AND THOMAS M. CHANCE, OF PHILADELPHIA, PENNSYLVANIA.

METHOD AND APPARATUS FOR PUMPING LIQUIDS.

1,109,108.

Specification of Letters Patent.

Patented Sept. 1, 1914.

Application filed January 30, 1913. Serial No. 745,150.

To all whom it may concern:

Be it known that we, HENRY M. CHANCE and THOMAS M. CHANCE, citizens of the United States, residing at Philadelphia, in the county of Philadelphia and State of Pennsylvania, have invented certain new and useful Improvements in Methods and Apparatus for Pumping Liquids, whereof the following is a specification, reference being had to the accompanying drawings.

Our invention relates primarily to improvements in methods of pumping liquids, and by the term "liquids" we mean to include simple liquids, mixtures of liquids and of liquids and solids capable of being pumped, but it may also be used in operating apparatus of certain types constructed for pumping or compressing air or gas.

Our improved method of pumping is especially adapted for use in operating internal-combustion pumps in which the pressure of an ignited combustible mixture acts directly upon liquid, or is transmitted to the liquid to be pumped by means of a piston or of a piston and plunger, but may also be used in operating pumps driven by any medium having high initial pressure and expansive force, such as steam or compressed air.

In describing an invention patented to us March 26th, 1912, U. S. Patent, Number 1,020,965, we have shown how a portion of the energy, especially of the high pressure energy developed during the early part of the power stroke of a heat engine, may be utilized to pump liquid against relatively high pressures and the balance of the energy developed by the power stroke may be utilized to pump liquid against lower pressures or to store energy in an accumulator, and we have also described the subsequent use of this stored energy, by reaction of the accumulator, to effect the return stroke of the engine and the compression of a new charge in the combustion chamber of said engine.

Our present invention is an improvement upon said method whereby the accumulator is dispensed with and the residual energy, represented by the momentum of the moving body of liquid, is utilized directly to effect the return stroke of a second heat engine and to compress the combustible charge in the combustion chamber of said engine.

The method may be carried out in an apparatus made by connecting two independent pump chambers by a conduit of dimen-

sions suitable for containing a body of liquid large enough to act efficiently as an oscillating flywheel in absorbing and giving out energy, each of the pump chambers being connected with valved intakes for liquid to be pumped and each pump chamber or the conduit extending from said pump chamber, being provided with a connection, controlled by a non-return valve, leading to a region of discharge. In some cases these two connecting conduits used as discharge conduits, may be merged into a single conduit connecting with the main conduit at a point between the two pump chambers, and in such cases one discharge valve or one set of discharge valves will act as discharge valves for both of the pump chambers.

The drawings Figs. I and II are vertical cross-sections of apparatus by which our method may be carried out and illustrate its application to pumps of three different types. Fig. III is a vertical view and section showing a different arrangement of apparatus similar to that shown by Fig. I. In the drawings like numbers refer to like parts. Fig. IV shows a modification of the apparatus shown by Fig. II, by which the apparatus may be used to pump larger quantities against lower pressures.

Fig. I illustrates its application to a type of pump chamber in which pressure is transmitted to the liquid in the pump chamber 1, by means of a plunger 2, operating through a piston rod 3, which may be connected to the piston of a two-stroke cycle by-pass scavenging internal-combustion cylinder or other similar single-acting reciprocating prime mover, and also to a type of pump chamber in which pressure is transmitted to the liquid in the pump chamber 4, by an ignited combustible mixture contained therein. This pump chamber 4, is in this case used also as a combustion chamber and is provided with a valved inlet 5, for combustible mixture and a valved exhaust 6, for the exhaust of the products of combustion and contains a float valve 7, by which the expansion of the gases and the quantity of liquid expelled from the pump chamber at each power stroke are controlled. It will be understood that the operation of the inlet and exhaust valves, the ignition of the combustible charge and the scavenging of waste products may be effected by means in common use for such purposes. Both pump chambers 1 and 4 are provided with inlet

valves 8 and 8^a for liquid, and suction supply conduits 9 and 9^a connecting with a supply of liquid to be pumped, conventionally shown as tanks 10 and 10^a. The pump chambers 1 and 4 are connected by a conduit 11, providing unobstructed communication between them. This conduit is virtually an elongated extension of the pump chambers 1 and 4. Connecting with this conduit 11, or if desired with the pump chambers 1 and 4, are two connecting conduits 12 and 12^a which connect the pump chambers 1 and 4 with discharge mains 13 and 13^a, which later may merge into a single discharge main 14. Connection between the connecting conduits 12 and 12^a, and the discharge mains 13 and 13^a is preferably made through air chambers 15 and 15^a, although such air chambers are not always essential to the efficient use of our method. At some point in each of the connections 12 and 12^a between the conduit 11 and the air chambers 15 and 15^a, non-return valves 16 and 16^a are placed, the drawing illustrating two positions of such valves.

The operation of our method as used with the described apparatus is as follows: The plunger 2 actuated by the ignition of a compressed combustible charge in the cylinder of a two-stroke cycle combustion chamber of the described type with the piston of which it is connected by means of the piston rod 3, communicates pressure to the liquid in the pump chamber 1 and this pressure is, by the liquid in conduits 11 and 12, transmitted to the region of discharge at the air chamber 15 causing liquid to be discharged and imparting momentum to the liquid in conduit 12, at the same time this pressure sets the liquid in conduit 11 in motion, liquid commencing to flow into the pump chamber 4, the upper part of which contains a charge of combustible mixture. As the pressure in the prime mover falls by reason of the expansion of the hot gases by which it is operated, the pressure communicated to the liquid in the pump chamber 1 by the plunger 2 decreases and soon drops to a pressure less than that against which liquid is being forced into 15, thereafter further discharge of liquid into 15 is maintained for a time by the momentum of liquid in the conduit 12, the liquid in this conduit comes to rest and the discharge valve 16 closes. During this period the pressure produced by the plunger 2 is still acting upon the liquid in the conduit 11, so that when the plunger 2 comes to rest at the end of its stroke the liquid in this conduit has relatively high velocity, and by its continued travel draws in a new increment of liquid through the inlet valve 8, and at the same time compresses the charge of combustible mixture in 4, and finally comes to rest and the inlet valve 8 closes. During this period of continued travel of the liquid

in 11, the waste products are exhausted and scavenged from the prime mover and a new charge of combustible mixture introduced therein. The compressed charge of combustible mixture in 4 is now ignited and the pressure produced causes the same cycle of events to occur in 11, 12^a and 15^a, liquid being discharged into 15^a the discharge valve 16^a, closing, and movement of the liquid in 11 starts the plunger 2 on its return stroke. The float valve 7 closing at the end of the expansion stroke in 4, new liquid is drawn through 8^a and the plunger 2 carried through the balance of its return stroke, the pressure exerted upon it being in turn transmitted to the piston of the prime mover and compressing a new charge of combustible mixture in said prime mover. After the closing of the float valve 7 and during the period of continued travel of liquid in the conduit 11, the waste products of combustion are exhausted through 6 and a new charge of combustible mixture introduced through 5.

For clearness in describing the operation of the method the drawing has been made with the two pumps facing each other and connected by a straight conduit and the two pumps used to illustrate the method are of two different types. It would not of course in practice often be desired to use the method with two pump chambers of different types. Under ordinary conditions the two pump chambers will be duplicates of each other, will be placed side by side, facing in the same direction and the conduit 11 will extend the same distance from each of the pump chambers and the two halves connected by a return bend of 180 degrees curvature; reactions being thus balanced. By adopting this form of construction the two pump chambers may be cast as a unit, one suction main supplying both chambers, one source of combustible mixture may be used to supply both pumps and a single exhaust pipe may be used to carry away the exhaust from both.

It is evident that the upper part of the pump chamber 4 used as a two-stroke cycle combustion chamber may be replaced by two four-stroke cycle combustion chambers acting alternately and giving a two-stroke cycle effect, such for instance as the twin combustion chambers described by us in U.S. Patent No. 1,011,410, issued December 12, 1911, or that the plunger 2 may be driven by the straight connected pistons of two tandem four-stroke cycle cylinders igniting alternately so that each pumping stroke of the plunger is a power stroke. In designing an apparatus of this type for operating our method, regard must be had to the relative lengths and diameter of the conduits 11 and 12 and 12^a, in order that the masses of liquid to be set in motion may be such as to secure the desired division of energy between that

used to discharge liquid and that used to impart velocity to the body of liquid contained in conduit 11. If the pressure against which liquid is to be pumped is relatively high it is advantageous to connect the conduits 12 and 12^a with the conduit 11 at or near the pump chambers 1 and 4, and to make the conduits 12 and 12^a relatively short or relatively large in diameter, as compared with the dimensions of the conduit 11 and vice versa. The apparatus shows but one conduit 11, connecting the two pump chambers 1 and 4, but it is evident that two or more such conduits may be used either simultaneously or at different times, and that conduits of different length and size may be used either singly or jointly to vary the velocity of the power stroke of the pump and to effect the required division of energy between that required for pumping and that required for compression of the combustible charge.

It is evident that the method may be carried out with many different forms of apparatus and with a great variety of actuating mechanism and we do not desire to limit ourselves to the particular type of apparatus described or shown, as our method may be used with any type of pump chamber from which liquid is expelled by pressure applied from any source of energy but it is especially adapted for use with internal-combustion engines because it provides a direct means whereby the combustible mixture in one combustion chamber is compressed by the energy of an ignited combustible mixture expanding in another combustion chamber.

While in most cases the intakes for liquid to be pumped will best be located at the pump chambers, such location is not essential to the successful operation of the method, for these intakes may connect with the conduit 11 at some distance from the pump chamber, or in some cases may connect with the conduits 12 and 12^a. When it is desired to use the method for pumping or compressing air or gas, no new liquid need be taken into the apparatus, and the apparatus may be constructed with the inlet valves 8 and 8^a and the discharge valves 16 and 16^a both located at or near the point where the connecting conduits 12 and 12^a connect with the air chambers 15 and 15^a.

The essentials of an apparatus for the operation of our method are two pump chambers in which liquid alternately may be subjected to pressure from some source of energy, (preferably from a medium having high initial pressure and expansive force), and which are connected by a conduit of suitable size and length providing unobstructed communication between them, one or more conduits (usually controlled by valves) connecting this conduit with the discharge main, and valved inlets to the ap-

paratus for the admission of the substance to be pumped.

Fig. II illustrates the use of our method applied to the operation of four internal-combustion chambers working on the four-stroke cycle. In this Fig. II, A, B, C and D are four internal-combustion cylinders, with pistons 2^a, 2^b, 2^c and 2^d, the cylinders being provided with inlets 5^a, 5^b, 5^c and 5^d for combustible mixture and outlets 6^a, 6^b, 6^c and 6^d for the exhaust of waste products of combustion. These inlets and exhausts may be equipped with inlet and exhaust valves and mechanism for operating them similar to those used in tandem four-stroke cycle internal-combustion engines, the movement for operating which may be taken from the exposed portion of the piston rods 3^{ab} and 3^{cd}, or from a tail-rod attached to either piston, or the valves may be operated by pressure transmitted from the pump chamber, or by floats or other devices in common use for such purposes. The pistons 2^a and 2^b and the pistons 2^c and 2^d are respectively connected together by the piston rods 3^{ab} and 3^{cd}. The lower part of the chambers B and D are connected with the intakes 9^b and 9^d controlled by inlet valves 8^b and 8^d, and the lower parts of the chambers A and C may also if desired be similarly connected with these intakes and with the conduit 11^{bd} by means of connections as indicated by the dotted lines 17^{ab} and 17^{cd}. The conduit 11^{bd} connects the chambers B and D and the conduit 12 connects this conduit 11^{bd} with a discharge main 14 through non-return valve 16 and the air-chamber 15. This drawing illustrates the type of construction in which the discharge conduits 12 and 12^a of Fig. I are replaced by a single discharge conduit.

The operation of our method with this apparatus is as follows: The combustion space in chamber A containing a charge of compressed combustible mixture, that in B being filled with waste gases (or with waste gases diluted with air if a scavenging charge of air has been introduced during the preceding exhaust period) that portion of the cylinder C above its piston being filled with combustible mixture and the cylinder D above its piston containing the products of combustion from a previous power stroke, the conduits and pump chambers containing liquid, the compressed charge in A is ignited, causing piston 2^a to actuate piston 2^b and to communicate pressure and movement to liquid in 11^{bd} and in 12, producing discharge of liquid from the conduit 12 into 14. The movement of liquid is 11^{bd} carries pistons 2^c and 2^d through their return stroke while liquid is entering the system through inlet valve 8^b, and the momentum of the moving liquid effects the simultaneous discharge of waste products from D and the compression of the combustible mixture in C. During the

outstroke of pistons 2^a and 2^b and while these pistons were transmitting the energy of the ignited combustible mixture in A to the liquid, a new charge of combustible mixture was drawn or admitted into B. The compressed charge in C is now ignited and the same sequence of events repeated, a new charge flowing into D, waste products being expelled from A and the combustible charge in B compressed; the compressed charge in B is then ignited, expelling waste products from C, drawing in a new charge into A and compressing the charge in D; the charge in D is now ignited, drawing in a new charge in C, expelling waste gases from B and compressing the charge in A, thus completing the whole cycle for the four cylinders.

This application of our method as illustrated by Fig. II develops a system of operating internal-combustion pumps that differs essentially both as to the cycle of events and results obtained from any method heretofore known or used. These differences may be noted as follows: 1, the whole period of expansion of an ignited charge is utilized for the admission of a new charge into another cylinder, 2, the new charge may be drawn in by energy directly transmitted from the expansion of the ignited charge, and not by the momentum of a moving body, 3, the waste products of combustion are expelled from one cylinder and the new charge compressed in another cylinder simultaneously, 4, the latter operations are effected partly by energy directly transmitted from the ignited charge and partly by energy from said charge stored in a moving body of liquid, there being no storage of energy in accumulators for subsequent use by reaction.

The operative portions of the last described type of apparatus are similar in many respects to those of a four cylinder twin tandem four-stroke cycle engine, with this material difference however that the two pairs of pistons are not linked together but are free to move independently of each other. The cylinders A, B, C and D of these four-stroke cycle machines are provided with customary igniting devices (unless operated by self-ignition) and these may be operated by the same mechanism used to control the exhaust valves. Automatic inlet valves may be used if desired. The clearance space is normally filled with waste gases at the end of the exhaust stroke, but these may be greatly diluted by admitting a scavenging charge of air during the expulsion of waste products. If it be desired to use the lower portions of the cylinders A and C as pump cylinders, this may readily be done by connecting them to the conduit 11, or by connecting cylinder A with cylinder B and cylinder C with cylinder D, in any desired way, one method by

which such connection can be made is indicated by the connecting conduits 17^{ab} and 17^{cd} shown by Fig. IV.

Fig. III illustrates the use of our method with one of the simplest forms of internal-combustion pump, the working pump chambers 1 and 4 being used also as two-stroke cycle internal-combustion cylinders without pistons. Inlet valves 8 and 8^a for liquid are shown, and intakes 9 and 9^a, with sources of supply of liquid 10 and 10^a. The reaction conduit 11 is common to both working chambers, and the possibility of lengthening it by introducing curves is illustrated by the drawing. Conduits 12 and 12^a connect chambers 1 and 4 with the discharge main 14 common to the discharge from both 12 and 12^a through the air chamber 15 and discharge valves 16 and 16^a. The two working chambers are provided with valved intakes 5, 5 for the admission of scavenging air and combustible mixture and valved outlets, 6, 6 for the exhaust of the products of combustion. The scavenging air and combustible mixture are admitted under pressure as is commonly practiced in the operation of two-stroke cycle internal combustion engines.

From the description of the operation of the working chamber 4 described in connection with Fig. I, the method of operation will be readily understood, the principal difference being that in this apparatus of Fig. III the ignited gases may be expanded to less than atmospheric pressure and the new increment of liquid thus drawn in. Expansion to such low pressure will not be necessary, if liquid be supplied to the intakes 9 and 9^a under a slight head.

Under certain conditions in operating the method for pumping against low heads the discharge valve may be unnecessary, the discharge flow in the conduit leading to the discharge main being practically continuous,—the momentum of liquid in this conduit from one power impulse not being entirely expended before the next succeeding power impulse.

It will be understood that the operation of our method as herein described may be used in combination with other methods of pumping liquids, such for instance as that described by us in United States Patent No. 1,026,637, patented May 14, 1912, or other methods heretofore used for the pumping of liquids, and that in the use of this method we do not desire to limit ourselves to the particular type or types of apparatus herein described.

Having described our invention, we claim,

1. A method of pumping liquid which consists in applying pressure, generated by the power impulse of a prime mover actuated by an elastic medium, to a confined body of liquid, a portion of which is inter-

posed between an inlet for liquid and a region of discharge and a portion of which is interposed between said prime mover and a second similar prime mover, in causing said pressure to commence the discharge of liquid at said region of discharge and simultaneously to cause said second prime mover to commence a return stroke thereof, in causing the movement of said second named portion of liquid after the completion of the power stroke of the first named prime mover to effect the completion of the return stroke of the second prime mover and simultaneously therewith to draw in a new increment of liquid.

2. A method of pumping liquids by means of a medium having high initial pressure and expansive force, which consists in causing said medium to impart pressure and movement to a body of liquid, a portion of which is interposed between a pump chamber containing liquid in operative relation to said high pressure medium and a pump chamber containing liquid in operative relation to a similar medium at relatively low pressure and a portion of which is interposed between an inlet for liquid and a relatively high-pressure discharge, in discharging a portion of the liquid interposed between said inlet and said discharge while said low-pressure medium is still at relatively low pressure, in permitting the movement of the liquid interposed between the said two pump chambers to increase the pressure of the medium at low pressure and to draw in a new increment of liquid through said inlet, and in causing said increase in pressure to bring the body of liquid interposed between the said pump chambers to rest prior to the return power stroke; whereby the elastic medium in operative relation to said first named pump chamber is expanded to relatively low pressure prior to its exhaust and the elastic medium in operative relation to the said second named pump chamber is compressed to relatively high pressure prior to its expansion in effecting the return power stroke and whereby each movement of said body of liquid is effected by a power stroke of said medium operating alternately on the liquid in the said two pump chambers.

3. A method of pumping liquids by the expansion of an ignited combustible mixture, which consists in causing said ignited combustible to impart movement to a body of liquid, a portion of which is interposed between an inlet for liquid and a region of relatively high pressure discharge and a portion of which is interposed between a pump chamber containing liquid that is in operative relation to said ignited combustible and a pump chamber containing liquid that is in operative relation to an unignited combustible mixture at relatively low pres-

sure, in causing said movement to commence the discharge of liquid at said region of discharge when the unignited combustible mixture is at relatively low pressure and in causing said movement to effect the compression of the said unignited combustible mixture to relatively high pressure.

4. A method of pumping liquids by the expansion of an ignited combustible mixture, which consists in causing said ignited combustible to impart movement to a body of liquid, a portion of which is interposed between an inlet for liquid and a region of relatively high pressure discharge and a portion of which is interposed between a pump chamber containing liquid that is in operative relation to said ignited combustible and a pump chamber containing liquid that is in operative relation to an unignited combustible mixture at relatively low pressure, in causing said movement to commence the discharge of liquid at said region of discharge when the unignited combustible mixture is at relatively low pressure, in causing said movement to effect the compression of the said unignited combustible mixture to relatively high pressure and to draw in a new increment of liquid through said inlet after said ignited combustible has expanded to relatively low pressure.

5. A method of pumping liquid which consists in applying pressure to liquid contained in a pump chamber which through a conduit is connected with a discharge main and which also has an unobstructed communication through another conduit with another pump chamber similarly connected with a discharge main, both of said chambers being connected with intakes for liquid to be pumped, and all of said conduits, connections and pump chambers containing liquid, in permitting liquid to discharge into said first named discharge main and in permitting liquid to flow into said second named pump chamber, in cutting off the application of pressure to said liquid in said first named chamber, in permitting liquid to continue to flow into said second named chamber and a new increment of liquid to flow in through the intake connecting with said first named chamber; whereby the energy of the power-stroke in said first pump chamber is partly used to discharge liquid and to impart velocity to the liquid flowing toward said discharge, (whereby said discharge is continued after the actuating pressure drops below the discharge pressure,) and is partly used to effect the return stroke in said second pump chamber and to impart velocity to liquid filling the conduit connecting the two pump chambers, whereby the return stroke in said second pump chamber is completed.

6. In a method of pumping liquids in which two pairs of four-stroke cycle work-

ing cylinders are used, and in each of which pairs the compression stroke in one working cylinder occurs simultaneously with the exhaust stroke in the other working cylinder, the improvement which consists in causing an ignited combustible mixture to impart movement to a body of liquid, a portion of which is interposed between an inlet for liquid and a region of relatively high pressure discharge, and a portion of which is interposed between a pump chamber containing liquid which is in operative relation to said ignited combustible mixture and a pump chamber containing liquid that is in operative relation to an unignited combustible mixture at relatively low pressure, in causing said movement to commence the discharge of liquid at said region of discharge when the unignited combustible mixture is at relatively low pressure and is causing said movement to effect the compression of said unignited combustible mixture to relatively high pressure.

7. A pump comprising in combination two independent pump chambers connected by a conduit providing unobstructed communication between the said chambers, a conduit connecting each of said pump chambers with a discharge main and permitting at all times free discharge into said main, valved inlets to connect said apparatus to a source of material to be pumped, means for alternately applying pressure to the liquid contained in each of said pump chambers, said pressure being greater than the pressure against which the material is to be pumped, and means for controlling the energy applied to each pump chamber, whereby liquid set in motion by energy applied to one pump chamber may continue in motion after the application of said pressure has ceased.

8. An internal combustion-pump comprising

ing in combination two independent pump chambers and a conduit connecting said chambers, said conduit being of such size and dimensions as may be required to contain a body of liquid adapted to be used as an oscillating flywheel or compensator efficiently to transmit, and to control the expenditure of, a portion of the energy developed during the power-stroke in one of said chambers to perform work in the other of said chambers, a conduit connecting said described apparatus with a discharge main and permitting at all times free discharge into said main and a valved inlet for the admission of the substance to be pumped.

9. An internal-combustion pump comprising in combination two independent pump chambers and a conduit connecting said chambers, said conduit being of such size and dimensions as may be required to contain a body of liquid adapted to be used as an oscillating flywheel or compensator efficiently to transmit, and to control the expenditure of, a portion of the energy developed during the power stroke in one of said chambers to perform work in the other of said chambers, a conduit connecting said described apparatus with a discharge main and permitting at all times free discharge into said main, a valved intake for the admission of the substance to be pumped and means for introducing combustible mixture, for igniting said mixture and for discharging the products of combustion.

In testimony whereof we have hereunto signed our names at Philadelphia, Pennsylvania, this 28th day of January, 1913.
